ATTORNEYS.

UNITED STATES PATENT OFFICE.

ROBERT JOHNSON, OF FLORESVILLE, TEXAS.

TIE-TAMPING DEVICE.

1,285,205.

Specification of Letters Patent. Patented Nov. 19, 1918.

Application filed January 5, 1918. Serial No. 210,419.

To all whom it may concern:

Be it known that I, ROBERT JOHNSON, a citizen of the United States, residing at Floresville, in the county of Wilson and State of Texas, have invented certain new and useful Improvements in Tie-Tamping Devices, of which the following is a specification.

This invention relates to new and useful improvements in a tie tamping device.

The object of the invention is to provide a device of the character described particularly adapted to be used in the construction and repair of railroad tracks and more particularly for the purpose of tamping the ties of said track.

With the above and other objects in view the invention has particular relation to certain novel features of construction, operation and arrangement of parts, an example of which is given in this specification and illustrated in the accompanying drawings, wherein,

Figure 1 is a side elevation of the device, Fig. 2 is a fragmentary plan view thereof, Fig. 3 is a transverse sectional view thereof, and

Fig. 4 is a fragmentary sectional view of the tamping rod.

Referring now more particularly to the drawings wherein like numerals of reference designate similar parts in each of the figures, the numeral 1 refers to the frame work of the machine which is mounted upon suitable trucks 2. Mounted upon the frame work are the A frames 3, 3 one on each side, said A frames being connected by a suitable cross beam as 4, and being strengthened by suitable cross braces as 5, thus forming a supporting frame which is hinged at its forward end to the framework 1, and having its rear end free to move vertically. A truck 6 is coupled to the front end of the machine and is provided to support the motor 7. Upstanding from the front end of the frame work 1 is a beam 8 whose upper end carries a pulley 9 and a cable 10 is attached at one end to the cross beam 4 and passes over said pulley and its other end is wound around a windlass 11 carried by the truck 6. By the use of this windlass the A frame may be elevated and lowered, through the cable 10, for the purposes hereinafter set forth. A manual lever 12 is pivoted at its lower end to the rear end of the frame work 1 and is provided with a ratchet face 13 which

is normally held in engagement with the corresponding ratchet face, carried by the frame work, through the pull spring 14. The A frames are thus normally held against vertical movement but when it is desired to elevate them, the ratchet teeth 13 may be disengaged by the manipulation of the lever 12 to permit their elevation, and the operative mechanism carried thereby. The lever 12 may be manipulated from the truck 6, through the rod 43, which is pivoted to the lower end of said lever. Mounted in suitable bearings in said A frames are the transverse shafts 15, 15 one of which has the pulley 16 fixed thereon over which operates the belt 17 which is driven from the motor 7. Fixed upon the respective shafts 15 are the intermeshing spur gear wheels 18, 18 through which rotation is imparted from one of said shafts to the other. Each of the shafts 15 is provided with a plurality of cranks 19 arranged in staggered relation and pivoted to these cranks are the corresponding tamping rods 20 which operate through alined bearings 21 in the transverse bearing bars 22, 22. These rods 20 are jointed near the shaft 15, are spaced apart, and formed with shock absorbers 20' as clearly shown in Fig. 4. The bearing bars 22 are slidable, lengthwise in the respective bearings 23, 23, which, in turn, are slidable upon the bases 24, 24 of the A frames 3, 3.

At each end of the machine are the short transverse shafts 25, 25, which are rotatably mounted in suitable bearings, and one of which has the sprocket 26 fixed thereon, which is driven from the sprocket 15', fixed on the shaft 15, through the sprocket chain 27, and also has the pulley 28, fixed thereon, through which rotation is imparted to the other shaft, through a belt 29, which operates on the pulley 30 fixed on said last mentioned shaft. Fixed to the inner ends of these shafts 25 are the miter gears 31, 31 which are in mesh with corresponding miter gears 32, 32, fixed upon the short lengthwise shafts 33, 33 which are rotatably mounted in suitable bearings carried by the frame. These shafts 33 each have the long cranks 34, 34, which are connected with the corresponding bearing bars 22, 22, through the connecting rods 35, 35. These rods are hinged at one end to the bearing bars 22, and their other ends have bearings which are slidable upon the wrists 35 and as the shafts 33 rotate the bearing bars 22 are re-

ciprocated a limited distance back and forth. A transverse shaft 36 is mounted in suitable bearings and is located midway between the bearing bars 22. At each end this shaft 5 has the oppositely extending arms 37, and links 38, 38 are pivoted at one end to the free ends of these arms and at their other to the respective bearings 23, 23. The shaft 36 also has an upstanding arm 39 fixed thereto, 10 to the upper end of which, one end of the link 40 is pivoted, and the other end of this link is pivoted to the manual lever 41 which in turn is pivoted at one end to the forward end of the machine. This lever 41 is normally held in a fixed position by means of the usual rack-and-dog arrangement 42 and through it the shaft 36 may be moved back 15 and forth and the opposing bearings 23, 23 thus forced apart or drawn together. In operation the tamping rods are reciprocated through the cranks of the shafts 15 and operate loosely through the bearings 21. As is shown in Fig. 1 these tamping rods are arranged in series or sets one set operating 20 on one side of the tie and the other set operating on the other side and the shafts 15 are spaced a sufficient distance apart so that the tamping rods will converge downwardly toward each other and will operate to force the tamping material under and against the sides of the ties and firmly pack the same, and the lowered ends of said tamping rods 25 may be spread apart or brought closely together through the manipulation of the manual lever 40, as hereinbefore explained, in accordance with the width of the tie being tamped or the range of movement which it is desired to give to said rods.

While the machine is in operation the 40 rotation of the shafts 33, 33 will operate, through the cranks 34, and the connecting rods 35, to oscillate the bearing bars 22 back and forth in their bearings so as to give considerable transverse range to the lowered 45 ends of the tamping rods so that all of the material adjacent to the ties will be thoroughly packed and tamped and a portion thereof forced under the ties.

When it is desired to move the machine forward the rack teeth 13 are released 50 through the lever 12 and the A frames are elevated, through the instrumentality described for that purpose, so that the lowered ends of the tamping rods 20 will clear the track as the machine is being moved. 55

What I claim is:—

1. A device of the character described including a frame, a series of tamping rods, a driving mechanism connected to and reciprocating the rods of each series, a pair 60 of transverse bearing bars spaced apart through the bearings of which the rods of the respective series operate, means for moving said bars toward and from each other, and a mechanism for reciprocating the bars laterally during the operation of said rods.

2. A device of the character described including a frame, a pair of transverse bearing members carried by the frame and 70 spaced apart, and provided with spaced bearings, tamping rods operating through the bearings of each member, means operatively connected with said rods for reciprocating the same, means through which said members may be moved toward and from each other, and a mechanism for oscillating said members during the operation of said rods.

3. A device of the character described 80 including a frame hinged at one end to a support, transverse bearing members carried by the frame and spaced apart, and provided with spaced bearings, tamping rods operating through said bearings, means for reciprocating said rods, means for oscillating said bearing members during the reciprocation of the rods, and means for elevating said frame work relatively to said support.

In testimony whereof I have signed my 90 name to this specification in the presence of two subscribing witnesses.

ROBERT JOHNSON.
